TELESCOPIC GUN SIGHT

John T. Armbruster, Niagara Falls, N.Y., assignor to American Optical Company, Southbridge, Mass.

Filed Sept. 12, 1960, Ser. No. 62,090

Term of patent 14 years

(Cl. D30—1)

FIG. 1 is a side elevational view of a telescopic gun sight showing my new design; and

FIG. 2 is a perspective view showing the top and other side thereof.

I claim:

The ornamental design for a telescopic gun sight, substantially as shown.
